UNITED STATES PATENT OFFICE.

THEOPHILUS P. CHANDLER, OF PHILADELPHIA, PENNSYLVANIA.

WIRE-SUPPORT.

No. 921,362.

Specification of Letters Patent.

Patented May 11, 1909.

Application filed July 14, 1908. Serial No. 443,524.

To all whom it may concern:

Be it known that I, THEOPHILUS P. CHANDLER, a citizen of the United States, and resident of the city and county of Philadelphia, State of Pennsylvania, have invented an Improvement in Wire-Supports, of which the following is a specification.

My invention has reference to electric and other wire supports and consists of certain improvements which are fully set forth in the following specification and shown in the accompanying drawings which form a part thereof.

The object of my invention is to provide a simple and efficient device for supporting electric and other wires, more particularly for use in connection with electric railways, which may be attached to the wire in a positive manner so as to grip or hold it firmly and without the necessity of brazing, soldering or other permanent means of union.

My object is also to provide a construction of suspended wire support which is adapted for supporting the wires from above, below or laterally; and my invention is more particularly directed to the immediate means by which the wire is supported, rather than the particular specific use to which it may be applied when employed in commercial use.

The invention is an improvement upon the class of suspension device set out in Letters Patent No. 779,640 dated January 10, 1905, and while embodying the great advantages of the construction therein set out also combine with them additional features of construction which secure greater strength and more perfect construction.

My invention consists in a support for an electric or other wire comprising two clamping body parts united in the direction of the length of the wire, said parts being provided with oppositely grooved portions for inclosing the sides of the wire and also with interlocking portions for preventing the spreading apart of the two clamping body parts and combined with detachable means for uniting the two parts in their interlocking engagement.

My invention further consists in the said wire support above specified when the opposite ends of the respective clamping parts are formed with additional grooved portion oppositely directed to the grooved body parts and an oblique entrance between the two said grooved portions of each of the clamping parts, whereby the said parts may be first

placed obliquely over the wire and the oppositely directed grooves of each clamping portion made to grip the wire from opposite sides by bringing them into alinement with the wire, so that not only is the wire gripped between the two clamping parts but it is also gripped between the oppositely directed grooved portions on each of the clamping parts.

My invention also comprehends details of construction which, together with the features above specified will be better understood by reference to the drawings, in which:

Figure 1 is a side elevation of a conductor support embodying my invention; Fig. 2 is a plan view of the same; Fig. 3 is an inverted view of the same; Fig. 4 is a cross section of the same; Fig. 5 is a view similar to Fig. 3 during the application of the supporting parts; Fig. 6 is an inverted view showing how the clamping parts are applied; Figs. 7 and 8 are end views showing my invention applied to conductors of different cross section; Fig. 9 is an elevation of a modification of my invention when the conductor is supported from below; Fig. 10 is a plan view of the same, and Fig. 11 is a perspective view of another modification of my invention.

A and B are two parts between which electric conductor F is gripped. These two parts are of similar construction and when placed into engaging position they interlock with each other both vertically and laterally and firmly hold the conductor without the necessity of soldering or brazing. These parts A and B are of considerable length where they engage the conductor and also have contracted necks, which when brought together form a screw threaded hub C over which the screwthreaded sleeve D is placed and by which the parts A and B are locked together. This hub C may also have an internal screwthreaded hole for reception of a bolt or screw L by which the suspending device may be attached to a support. In Fig. 1 this screw L is held in the insulator N, such as attached to cross wires in electric railways.

In Fig. 9 the bolt L is employed as the means of clamping the conductor support A B upon an arm N of any permanent fixture such as a cross arm or bracket of a pole. The parts A and B have their opposing lower parts internally grooved as at E to receive and clamp the conductor F between them. The opposite ends of the parts A B are respectively

provided with parts A' and B' which are also grooved and fitted upon the faces of the conductor F opposite to those gripped by the grooves of the corresponding body parts A and B. As these end portions A' B' extend to both sides of the conductor the grooved part E on one side is cut away as at K and the grooved parts A' and B' are cut away as at K' so as to form a wide throat J for reception of the conductor F to each of the parts A and B.

To apply the parts A and B, they are first placed diagonally across the conductor F as shown in Fig. 6, then pressed upon the conductor and subsequently turned into alignment therewith, as shown in Fig. 5, and ultimately forced tightly against the conductor and pushed together endwise until they engage as in Figs. 1, 2 and 3. In this condition, the parts A and B will directly clamp the conductor F between their grooved parts in the same transverse alignment, and the end parts A' and B' will clamp the conductor from opposite sides and also respectively in opposite directions to the main body parts A B. In other words, the parts A and A' grip the conductor upon opposite sides; and likewise, the parts B B' grip the conductor upon opposite sides.

From this, it will be seen that each of the two parts A B of the support will individually sustain the conductor and that both of the said parts together grip the conductor in the same transverse plane.

To lock the two parts A B together adjacent to the conductor, I provide each of the said parts with a vertical tongue H and a longitudinal tongue I at one end and with corresponding vertical undercut portions H' and recesses I' on the other end, whereby the tongues of each of the said parts A B will fit into the undercut portion and recesses of the other of said parts. The vertical tongues H and undercuts H' interlock the parts A B together in a horizontal plane and the tongues I and recesses I' interlock the parts A B together both vertically and laterally. It is evident that either the parts H H' or the parts I I' may be omitted if desired; and more broadly considering my invention, both of said sets of parts H H' and I I' may be dispensed with. It is also evident that instead of interlocking the parts A B at both ends, they may be interlocked at one end only, as preferred.

In Figs. 1 to 6 inclusive I have shown my invention adapted as a hanger such as may be used in electric railways, whereas in Figs. 9, 10 and 11 I have shown the conductor or wire support inverted and sustaining the conductor or wire from below, in which position it may act as a rail. These are the normal uses of my invention, but it is evident that the parts A B may extend from the conductor in any direction desired.

In Figs. 7 and 8, I have shown the support having the grooved portions E shaped to engage a grooved form of conductor. While it is most desirable to have the surface of the conductor F exposed continuously along its contact surface, this is not essential as the parts A B may be extended so as to envelop to a greater or less extent the conductor.

While my invention is especially useful as a supporting device for suspended electric wires or conductors and has been more fully described in connection with such use, I do not restrict myself to any use as the supporting device may be used for wires or rods adapted for any purpose. When constructed as in Figs. 9, 10 and 11 it is especially well adapted for use of the wire or rod as a rail or trackway as in telpher systems and may or not, as desired, also conduct electric energy.

In Fig. 11 the body parts A and B are flanged and rest directly upon the cross arms or ties to which they are bolted or spiked. I have used the term "conductor" in a broad sense irrespective of whether it is intended for conveying current or not and hence do not wish to be limited in any manner to specific applications of my invention.

I have shown my invention in the form in which it is excellently adapted for commercial use but I do not limit myself to the details as these may be modified without departing from the spirit of the invention.

Having now described my invention, what I claim as new and desire to secure by Letters Patent, is:—

1. In a supporting device for wires, the combination of two overlapping parts arranged to conjointly clamp the wire to support it said parts each having near one end of its wire-receiving portion a groove bounded by opposing sides and an oblique throat between the said grooved portion and the remaining portion, and means for securing the two overlapping parts rigidly together, whereby the said overlapping parts may be first adjusted to the wire by being placed obliquely thereon and then turned parallel therewith and moved endwise into overlapping engagement.

2. In a supporting device for wires, the combination of two interlocking parts arranged to conjointly clamp the wire to support it said parts each having near one end of its wire-receiving portion a groove bounded by opposing sides one of which is of less depth than the other and an oblique throat between said grooved portion and the remaining portion, and means for securing the two interlocking parts rigidly together, whereby the said two interlocking parts may be first adjusted to the wire by being placed obliquely thereon and then turned parallel therewith and moved into interlocking engagement.

3. A supporting device for wires consisting of two interlocking body parts detachably connected together and each body part having a portion of its length provided with a shallow lateral groove only and the remaining portion of its length provided with a deep groove the walls of which are symmetrically disposed at approximately ninety degrees with the groove of the first mentioned portion.

4. In a supporting device for wires the combination of the wire, with two interlocking parts each having two grooved portions respectively gripping opposite sides of different portions of the wire, and means for retaining the said interlocking parts in engagement when in clamping position.

5. In a supporting device for wires, the combination of the wire, with two grooved parts said parts each having two grooved portions each respectively gripping opposite sides of the wire at different places in its length and in which one of the grooved gripping portions of each of the parts is arranged to grip the wire at different portions of its length than is gripped by the grooved gripping portions of the other part and said parts also having means for interlocking when in clamping position, and means for locking the two parts in their interlocked positions.

6. In a supporting device for wires the combination of the wire, with two interlocking parts each having a grooved portion for respectively gripping opposite sides of the same part of the wire when in clamping

position and said parts also having clamping portions respectively located upon opposite ends and arranged to grip opposite sides of the wire at different places in its length and also different from the portions of the wire gripped by the joint action of the two parts.

7. In a support for wires, the combination of a wire, with two body parts arranged to be placed together to form a groove in which the wire is clamped and said parts each having one end shaped to fit over both sides of the wire and further having interlocking tongues and grooves to lock the two body parts against horizontal displacement laterally to the wire, and means for clamping the two parts in their interlocked positions.

8. A supporting member for a wire support consisting of the body part A having a groove E for the wire, a hub portion adjacent to the grooved body, and a gripping end portion A' having a groove for the wire, the two grooved portions arranged in opposite directions at a distance apart and constructed so as at one time to grip opposite sides of the wire at different places in its length and said body portion also having an undercut part H' and a recess I' at one end and tongues H and I at the other end, all substantially as described.

In testimony of which invention, I have hereunto set my hand.

THEOPHILUS P. CHANDLER.
